CLAIM

The ornamental design for a textile, as shown and described.

DESCRIPTION

The file of this patent contains at least one drawing/photograph executed in color. Copies of this patent with color drawing/photograph will be provided by the Office upon request and payment of the necessary fee.

FIG. 1 is a top plan view of a textile showing my new design;

FIG. 2 is a perspective view of the textile of FIG. 1 shown in a used condition with an insole in broken lines;

FIG. 3 is a top plan view of FIG. 2; and,

FIG. 4 is a right side elevational view of FIG. 2.

The dash-dot-dash broken line illustrates a boundary that forms no part of the claimed design. The dash-dash broken lines in FIGS. 2-4 illustrate environmental subject matter of the textile applied to an exemplary insole and form no part of the claimed design.
